Primary Examiner — Kevin K Rudzinski*Assistant Examiner* — Kimberly Barnes(74) *Attorney, Agent, or Firm* — Vorys, Sater, Seymour and Pease LLP(57) **CLAIM**

The ornamental design for a tile, as shown and described.

DESCRIPTION

FIG. 1 is a top plan view of a tile showing my new design. FIG. 2 is an enlarged view of the circumscribed area in FIG. 1.

FIG. 3 is an enlarged view of the circumscribed area in FIG. 2; and,

FIG. 4 is a side elevation view of the tile in FIG. 1, with all elevation views being identical thereof.

The evenly broken lines indicate enlarged partial views in figures. The dot-dash broken lines in FIG. 4 depict portions of the tile that form no part of the claimed design.

The depicted surface of the tile is flat.

The tile may be used as covering for floors, walls or other surfaces.
